INSECT CATCHER

Neil W. Callahan, Jr., 18517 E. 7 St. N.,
Independence, Mo. 64050

Filed Mar. 27, 1968, Ser. No. 11,154

Term of patent 14 years

(Cl. D22—19)

FIGURE 1.

FIGURE 2.

FIGURE 3.

FIGURE 4.

FIGURE 5.

FIGURE 1 is a side elevation of an insect catcher, showing my new design;

FIGURE 2 is a front elevation thereof;

FIGURE 3 is a top plan view thereof;

FIGURE 4 is the opposite side elevation thereof; and

FIGURE 5 is a rear elevation thereof.

I claim:

The ornamental design for an insect catcher, as shown.
